OVERHEAD TRAVELING DISPENSER UNIT

Bruce A. Schiltz, Wolsey, S. Dak.

Application February 3, 1958, Serial No. 712,789

21 Claims. (Cl. 137—355,17)

The invention herein has relation to an overhead dispenser unit devised to be especially useful for the purpose of selectively servicing automotive vehicles in a row side by side, as for example, on parking lots, with gasoline, water and air.

In the accompanying drawings forming a part of this specification,

Fig. 1 is a view of a dispenser unit made according to the invention showing a carriage thereof in end elevation and booms thereof in side elevation;

Fig. 2 is a plan view, partially broken away, of the dispenser unit as it would appear from the position of line 2—2 in Fig. 1;

Fig. 3 is a view of the dispenser unit disclosing the carriage thereof in side elevation and a boom thereof in end elevation, as said dispenser unit would appear from the position of line 3—3 in Fig. 1;

Fig. 4 is an enlarged detail sectional view, taken substantially on line 4—4 in Fig. 1;

Fig. 5 is a detail sectional view taken substantially on line 5—5 in Fig. 4;

Fig. 6 is an enlarged fragmentary side elevational view disclosing an end portion of a boom of the dispenser unit and a display case thereon; and

Fig. 7 is an enlarged detail sectional view taken on line 7—7 in Fig. 2.

Spaced, upright posts 10 support parallel bracket members 11 at opposite sides of the upright posts, and a horizontal channel member 12 is between the bracket members and above the posts and supported thereby. The upright posts 10 extend from the longitudinal center of an elongated rectilinear base 13 for said upright posts which divides a parking space into sections one of which is at either side of the rectilinear base. Automotive vehicles, such as 14, are to be parked in a row along the length of and in adjacent relation to each of the opposite sides of said rectilinear base.

Spaced, parallel, elongated I-beams, each denoted 15, are supported upon bracket members 11 at opposite sides of and in parallel relation to the upright posts 10 and the horizontal channel member 12. Each I-beam 15 includes a lower flange portion 16 rested upon bracket members at the same side of said upright posts and horizontal channel member and an upper flange portion 17. The upper flange portions 17 of the I-beams 15, respectively, are in a single horizontal plane above the elevation of automotive vehicles to be supplied with gas, water and air by the dispenser unit.

A carriage 18 of the dispenser unit is supported upon the upper flange portions 17 of the I-beams 15 for longitudinal movement along said I-beams. As disclosed, the opposite ends of spaced, transversely extending shafts 19, one adjacent each of the opposite ends of said carriage and suitably and conveniently rotatably mounted thereon, fixedly support rollers 20 which are rideable upon the I-beam at the corresponding side of the carriage. Also, a lower portion of said carriage supports longitudinally spaced, outwardly extending projections, each indicated

2

21, which support rollers 22 in proximate relation to the internal surface of the body and a lower surface of the upper flange portion of the I-beam at the corresponding side of the carriage. The projections 21 and rollers 22 are for maintaining the rollers 20 in proper and intended position on the I-beams and for precluding the possibility of tilting of said carriage.

The carriage 18 is of rectilinear configuration and constitutes a housing for elements of the dispenser unit, and 10 horizontal hollow booms, each represented 23, are supported on the housing of said carriage and extend outwardly from opposite sides thereof. The hollow booms are of duplicate construction, except that one is right and the other left, and in aligned relation, as well as in the 15 plane of and perpendicular relation to the carriage and its housing. Said hollow booms also contain elements of the dispenser unit.

Spaced, transverse shafts, denoted 24 and 25, respectively, are rotatably mounted in the housing of the carriage. 20 The transverse shaft 24 fixedly supports aligned drums, denoted 26 and 27, respectively, separated by annular partitions, each represented 28, also rigid with said transverse shaft. The transverse shaft 25 fixedly supports aligned drums, indicated 29 and 30, respectively, separated by annular partitions, each designated 31. A gear 32 fixedly supported on the transverse shaft 24 is in mesh with a gear 33 fixedly supported on the transverse shaft 25.

Hoses for water, high test gas and regular gas are indicated 34, 35 and 36, respectively, and a flexible cable 30 for lead wires, from a source not shown, is represented 37. The housing of the carriage 18 is open at the bottom and at an end thereof, the left end in Figs. 4 and 5, to receive the hoses 34, 35, 36 and the flexible cable 37, and the latter extend upwardly through an opening 38 in an upright post 10 and along the upper surface of the channel member 12. Said hoses also extend from sources of water and gas not shown, and the portions of the hoses and flexible cable at and in adjacent relation to the opening 38 are immovable during operation of the dispenser unit. That is, the hoses and flexible cable are retained in fixed relation to their sources of supply and to the upright post through which they extend.

The high test gas hose 35 rides the surface of an idler 39 opposite the location of entry of said high test gas hose into the housing of the carriage 18 and thence winds in clockwise direction around the drum 27. The idler 39 is on a transverse stub shaft in the carriage housing parallel with and in adjacent relation to the upper surface of the channel member 12. The interior end of the high test gas hose 35 is in communication, by way of a slip ring structure 40, with a tubular connection 41 which in turn is connected with a conduit 42 for high test gas. The conduit 42 extends through the housing of the carriage 18 and into and along the length of each of the hollow booms 23.

The regular gas hose 36 rides the surface of an idler 43 opposite the location of entry of said regular gas hose into the housing of the carriage and thence winds in counter-clockwise direction around the drum 30. The idler 43 is on a transverse stub shaft in the carriage housing parallel with and in adjacent relation to the upper surface of the channel member 12. The interior end of the regular gas hose 36 is in communication, by way of a slip ring structure 44, with a tubular connection 45 which in turn is connected with a conduit 46 for regular gas. The conduit 46 extends through the housing of the carriage and into and along the length of each of the hollow booms 23.

The water hose 34 rides the surface of an idler, similar to the idler 39, and thence winds in clockwise direction around the drum 26. The interior end of said water hose is in communication, by way of a slip ring structure 47, with a tubular connection 48 which in turn is connected

at 49 with a water dispensing hose 50 wound upon a reel 51. The water dispensing hose extends downwardly through the base of the housing of the carriage. The reel 51 unwinds in response to downward pulling of said water dispensing hose and is spring actuated to be wound up when the water dispensing hose is released. A valve, not shown, will control flow of water out of the water dispensing hose.

The flexible cable 37 rides the surface of an idler, similar to the idler 43, and thence winds in counterclockwise direction around the drum 29. The interior end of said flexible cable is connected, by a slip ring structure 52, with a cable 53 containing lead wire for circuits of several different electric motors which the dispenser unit employs.

A reversible electric motor 54, suitably and conveniently supported in the housing of the carriage 18, is for winding the hoses 34, 35, 36 and the flexible cable 37 upon and unwinding said hoses and flexible cable from their respective drums, as well as for accomplishing travel of the carriage 18 in either direction along the I-beams 15.

A chain 55 rides a pinion 56 fixed on the drive shaft of the motor 54 and also rides a gear fixed on a stub shaft 57 supported in the carriage housing. A chain 58 rides a pinion 59 fixed on the stub shaft 57 and also rides a gear 60 concentric and rigid with the gear 32. A gear upon and rigid with the stub shaft 57 is in mesh with a gear upon and rigid with a stub shaft 61. A chain 62 rides a pinion 63 fixed on the stub shaft 61 and also rides a gear 64 concentric and rigid with one of the transverse shafts 19 fixedly supporting a roller 26.

An electric motor 65 in the housing of the carriage 18 is for driving a compressor 66 for maintaining air under pressure in a reservoir 67. A tubular connection 68 for air under pressure leads from the reservoir to a conduit 69 which extends through said housing into and along each of the hollow booms 23. An air dispensing hose 70 in the outer end portion of each hollow boom 23 extends downwardly, as at 71, through a lower wall of a display case 72 rigid with the corresponding hollow boom. The air dispensing hoses 70 are wound upon reels 73 in the hollow booms, and the outer ends of the conduit 69 are connected, as at 74, with the interior ends of the air dispensing hoses 70. The reels 73 unwind in response to pulling the air dispensing hoses downwardly and are spring actuated to be wound up when said air dispensing hoses are released. Valves, not shown, will control flow of air through the air dispensing hoses.

The opposite ends of the conduit 42 for high test gas lead into casings 75 in outer end portions of the booms 23, and high test gas dispensing hoses 76, wound on reels 77, lead from said casings by way of tubular connections 78 to outlet nozzles 79. The casing 75 will contain usual gas pumps, not shown, and the dispensing of high test gas will be accomplished in ordinary manner. The reels 77 will unwind in response to pulling the high test gas hoses downwardly and be spring actuated to be wound up when said high test gas hoses are released.

The opposite ends of the conduit 46 for regular gas lead into casings 80 in outer end portions of the booms 23, and regular gas dispensing hoses 81, wound on reels 82, lead from the casings by way of tubular connections 83 to outlet nozzles 84. The casings 80 will contain usual gas pumps, and the dispensing of regular gas will be accomplished in ordinary manner.

The construction and arrangement will be such that the circuits for the reversible electric motor 54 will be broken when any of the gas dispensing hoses, or the water dispensing hose, or an air dispensing hose, is in use, thus to insure that the dispenser unit will remain stationary while being employed to service automotive vehicles. Referring to Fig. 7 of the drawings, the nozzles 79 and 84 there shown are situated as when in inoperative position to maintain switches, denoted 85 and 86, respectively, in the closed condition of circuits for the motor 54. When either of the nozzles is removed from the corresponding

display case, the circuits for said motor 54 will be broken. Interlocks for preventing travel of the carriage 18 when any of the hoses is in use can be employed. Or a manually operated switch for opening the circuits for the motor 54 when this is intentional can be included.

Meters 87, at the locations where gas is dispensed, employed to display the amount and value of each purchase, can be of usual or preferred construction.

When an automotive vehicle which is not aligned with the dispenser unit is to be serviced, with gas, water and/or air, a circuit for the reversible electric motor 54 will be closed, as by manually actuating a switch, to cause said electric motor to advance the dispenser unit in appropriate direction to be aligned with the automotive vehicle, and the circuit will be broken when the dispenser unit has reached the intended and proper position. The hoses 34, 35, 36 and the flexible cable 37 will be wound up on the drums with advancement of the dispenser unit in one direction and unwound from the drums and laid out flat on the channel member 12 with advancement of the dispenser unit in opposite direction. Servicing of automotive vehicles will be accomplished in the customary manner while the dispenser unit is retained in stationary position.

The winding up and unwinding of the hoses and flexible cable and travel of the carriage 18 to extent and in direction to correspond are accomplished by the reversible electric motor 54 through the instrumentality of a unitary mechanism.

What is claimed is:

1. In a unit for dispensing a fluid, an elongated member, a carriage, devices supporting said carriage upon and for longitudinal movement along said elongated member, a rotatable element upon the carriage, a hose for fluid to lead from a source of supply thereof along the elongated member mounted on said rotatable element to be wound thereon and unwound therefrom, a conduit for the fluid extending from said hose, and means for selectively advancing said carriage in either of opposite directions along said elongated member and for causing said hose to be wound upon the rotatable element in response to advance of the carriage in one direction and unwound from said rotatable element in response to advancement of said carriage in opposite direction.

2. In a unit for dispensing a fluid, an elongated member, a carriage, devices supporting said carriage upon and for longitudinal movement along said elongated member, a rotatable element upon the carriage, a hose for fluid to lead from a source of supply thereof along the elongated member mounted on said rotatable element to be wound thereon and unwound therefrom, a conduit for the fluid extending from said hose, a slip connection between an outlet end of said hose and said conduit, and means for selectively advancing said carriage in either of opposite directions along said elongated member and for causing said hose to be wound upon the rotatable element in response to advance of the carriage in one direction and unwound from said rotatable element in response to advancement of said carriage in opposite direction.

3. In a unit for dispensing a fluid, an elongated member, a carriage, devices supporting said carriage upon and for longitudinal movement along said elongated member, a boom supported by said carriage, a rotatable element upon the carriage, a hose for fluid to lead from a source of supply thereof along the elongated member mounted on said rotatable element to be wound thereon and unwound therefrom, a conduit for the fluid extending from said hose along said boom, and means for selectively advancing said carriage in either of opposite directions along said elongated member and for causing said hose to be wound upon the rotatable element in response to advance of the carriage in one direction and unwound from said rotatable element in response to advancement of said carriage in opposite direction.

4. In a unit for dispensing a fluid, an elongated member, a carriage, devices supporting said carriage upon

to advancement of the carriage in one direction and unwound from said rotatable element in response to advancement of said carriage in opposite direction.

13. In a unit for dispensing gasoline and air, an elongated member, a carriage, devices supporting said carriage upon and for longitudinal movement along said elongated member, a boom supported by said carriage, a rotatable element upon the carriage, a hose for gasoline to lead from a source of supply thereof along the elongated member mounted on said rotatable element to be wound thereon and unwind therefrom, a conduit for gasoline extending from said hose along said boom, a reservoir on said carriage, mechanism for providing air under pressure in said reservoir, a connection for air leading from the reservoir along said boom, and means for selectively advancing said carriage in either of opposite directions along said elongated member and for causing said hose to be wound upon the rotatable element in response to advancement of the carriage in one direction and unwind from said rotatable element in response to advancement of said carriage in opposite direction.

14. In a unit for dispensing gasoline and air, an elongated member, a carriage, devices supporting said carriage upon and for longitudinal movement along said elongated member, a boom supported by said carriage, a rotatable element upon the carriage, a hose for gasoline to lead from a source of supply thereof along the elongated member mounted on said rotatable element to be wound thereon and unwind therefrom, a conduit for gasoline extending from said hose along said boom, a slip connection between an outlet from said hose and said conduit, a reservoir on said carriage, mechanism for providing air under pressure in said reservoir, a connection for air leading from the reservoir along said boom, and means for selectively advancing said carriage in either of opposite directions along said elongated member and for causing said hose to be wound upon the rotatable element in response to advancement of the carriage in one direction and unwind from said rotatable element in response to advancement of said carriage in opposite direction.

15. In a unit for dispensing gasoline and air, an elongated member, a carriage providing a housing, devices supporting said carriage upon and for longitudinal movement along said elongated member, a hollow boom supported by said carriage, a rotatable element in said housing, a hose for gasoline to lead from a source of supply thereof along the elongated member mounted on said rotatable element to be wound thereon and unwind therefrom, a conduit for gasoline extending from said hose into said hollow boom, a slip connection between an outlet from said hose and said conduit, a reservoir on said carriage, mechanism for providing air under pressure in said reservoir, a connection for air leading from the reservoir into and along said hollow boom, and means for selectively advancing said carriage in either of opposite directions along said elongated member and for causing said hose to be wound upon the rotatable element in response to advancement of the carriage in one direction and unwind from said rotatable element in response to advancement of said carriage in opposite direction.

16. In a unit for dispensing gasoline and air, an elongated member, a carriage, devices supporting said carriage upon and for longitudinal movement along said elongated member, booms at opposite sides of the elongated member supported by said carriage, a rotatable element upon the carriage, a hose for gasoline to lead from a source of supply thereof along the elongated member mounted on said rotatable element to be wound thereon and unwind therefrom, a conduit for the gasoline extending from said hose along each of said booms, a reservoir on said carriage, mechanism for providing air under pressure in said reservoir, a connection for air

leading from the reservoir along each of said booms, and means for selectively advancing said carriage in either of opposite directions along said elongated member and for causing said hose to be wound upon the rotatable element in response to advancement of the carriage in one direction and unwind from said rotatable element in response to advancement of said carriage in opposite direction.

17. In a unit for dispensing gasoline and air, an elongated member, a carriage providing a housing, devices supporting said carriage upon and for longitudinal movement along said elongated member, hollow booms supported by and extending outwardly from opposite sides of said carriage, a rotatable element in said housing, a hose for gasoline to lead from a source of supply thereof along the elongated member mounted on said rotatable element to be wound thereon and unwind therefrom, a conduit for the gasoline extending from said hose into each of said hollow booms, a reservoir on said carriage, mechanism for providing air under pressure in said reservoir, a connection for air leading from the reservoir along and into each of said hollow booms, and means for selectively advancing said carriage in either of opposite directions along said elongated member and for causing said hose to be wound upon the rotatable element in response to advancement of the carriage in one direction and unwind from said rotatable element in response to advancement of said carriage in opposite direction.

18. In a unit for dispensing gasoline, water and air, an elongated member, a carriage providing a housing, devices supporting said carriage upon and for longitudinal movement along said elongated member, hollow booms supported by and extending outwardly from opposite sides of said carriage, rotatable elements in said housing, hoses for gasoline and water to lead from a source of supply thereof along the elongated member mounted on several of said rotatable elements to be wound thereon and unwind therefrom, a conduit for gasoline extending from said gasoline hose into each of said hollow booms, a flexible cable for lead wires to extend from a source of electrical supply along said elongated member mounted on a rotatable element to be wound thereon and unwind therefrom, a reservoir on said carriage, mechanism for providing air under pressure in said reservoir, a connection for air leading from the reservoir along and into each of said hollow booms, and means for selectively advancing said carriage in either of opposite directions along said elongated member and for causing said gasoline and water hoses and said flexible cable to be wound upon the corresponding rotatable elements in response to advancement of the carriage in one direction and unwind from said corresponding rotatable elements in response to advancement of said carriage in opposite direction.

19. The combination as specified in claim 18, and a slip connection between said gasoline hose and said conduit for gasoline.

20. In a unit for dispensing a fluid, an elongated member, a carriage, devices supporting said carriage upon and for longitudinal movement along said elongated member, a rotatable element upon the carriage, a hose for fluid to lead from a source of supply thereof along the elongated member mounted on said rotatable element to be wound thereon and unwind therefrom, a conduit for the fluid extending from said hose, first means for selectively advancing said carriage in either of opposite directions along said elongated member, second means for causing said hose to be wound upon the rotatable element in response to advancement of the carriage in one direction and unwind from said rotatable element in response to advancement of said carriage in opposite direction.

21. In a unit for dispensing a fluid, an elongated member, a carriage, devices supporting said carriage upon and for longitudinal movement along said elongated mem-

ber, a boom rigid with said carriage, a rotatable element upon the carriage, a hose for fluid to lead from a source of supply thereof along the elongated member mounted on said rotatable element to be wound thereon and unwound therefrom, a conduit for the fluid extending from said hose along said boom, first means for selectively advancing said carriage in either of opposite directions along said elongated member, and second means for causing said hose to be wound upon the rotatable element in response to advancement of the carriage in one direc-

5

tion and unwound from said rotatable element in response to advancement of said carriage in opposite direction.
